UNITED STATES PATENT OFFICE.

LAURENCE E. TOPHAM, OF BEVERLY, MASSACHUSETTS, ASSIGNOR TO UNITED SHOE MACHINERY COMPANY, OF PATERSON, NEW JERSEY, A CORPORATION OF NEW JERSEY.

SEWING-MACHINE.

1,099,326.

Specification of Letters Patent. Patented June 9, 1914.

Application filed August 23, 1911. Serial No. 645,591.

To all whom it may concern:

Be it known that I, LAURENCE E. TOPHAM, a citizen of the United States, residing at Beverly, in the county of Essex and State of Massachusetts, have invented certain new and useful Improvements in Sewing-Machines; and I do hereby declare the following to be a full, clear, and exact description of the invention, such as will enable others skilled in the art to which it appertains to make and use the same.

The invention relates to sewing machines such as are used in the manufacture of boots and shoes, and more particularly to devices and mechanisms for facilitating the removal of a completed shoe and the starting of the seam at the beginning of the sewing operation on a succeeding shoe.

It has heretofore been proposed to provide inseam sewing machines with mechanism for reversing the cycle of operations in stopping the machine at the completion of the sewing so that the needle is retracted while its hook is empty to free it from the thread, and is brought to rest in position where it does not interfere with the removal of the shoe or the insertion of the succeeding shoe.

One object of the invention is to provide novel and improved mechanism for thus reversing the cycle of operations at the completion of the sewing which is well adapted for use on high speed machines, and which will operate in a uniformly reliable manner, and without undue shock and wear upon the parts. To this end one feature of the invention contemplates the provision in an inseam sewing machine of mechanism which is thrown into operation at the completion of the sewing to apply a friction brake at a certain point in the cycle of operations of the machine which gradually retards the forward movement of the machine, and then drives the machine in a reverse direction to stopping position at a comparatively slow speed. The friction brake acts to absorb the energy due to the forward movement of the machine, and to gradually and quickly retard or arrest the forward movement without undue strain on the parts, and the reverse driving mechanism moves the parts back to stopping position at a speed which is unaffected by the forward speed of the machine, so that the parts may be brought to rest with uniform accuracy and in a uni-

formly reliable manner. It is preferred to so construct the braking and reversing mechanism that the forward movement of the machine will be arrested by the brake, although this is not essential to the broader scope of the invention, as the reversal may take place after the braking has sufficiently reduced the speed of the machine to enable the reversal to be properly effected. The braking and reverse driving and stopping mechanism may be of any suitable construction, but for the sake of simplicity it is preferred to so construct the reverse driving mechanism that when it is thrown into action it will first act as a brake to gradually arrest the forward movement of the machine, and will then act to drive the machine at a slow speed back to the desired stopping point.

In the simplest and most desirable form of the invention which has thus far been devised the braking and reverse is effected by a reversely rotating friction clutch member coöperating with a friction clutch member connected with the cam shaft of the machine. The clutch members are automatically engaged at a predetermined point in the rotation of the cam shaft, and first act as a friction brake which allows a limited forward rotation of the cam shaft, and then after the slip between the clutch members ceases, they act as a driving clutch to turn the cam shaft in a reverse direction until the clutch is disengaged and the return movement of the cam shaft arrested. Inseam sewing machines have also heretofore been provided with devices for severing and holding the welt after the sewing operation has been completed and the machine brought to rest, and have also been provided with devices for determining the length of welt which may be drawn forward by the operator in bringing the shoe into position for the action of the welt holding and severing devices.

It is a further object of the present invention to provide novel and improved mechanism for actuating the welt severing and holding devices whereby the welt may be more quickly severed and held and with less manipulation on the part of the operator than has heretofore been required. To this end a further feature of the invention contemplates the provision of mechanism which is controlled but not operated by the opera-

tor for actuating the welt severing and holding devices to grip and hold the welt. With this construction the welt severing and holding devices are rapidly operated in a uniformly reliable manner without any material exertion on the part of the operator. To further increase the rapidity with which the welt may be severed and held, the invention also contemplates throwing into operation the actuating mechanism for the welt severing and holding devices by the drawing forward of the shoe to bring the welt into position to be acted upon by the welt severing and holding devices.

The invention also includes certain further features of construction and combinations of parts which are hereinafter described and set forth in the claims.

The various features of the invention will be readily understood from an inspection of the accompanying drawings and the following detailed description of the mechanism illustrated therein.

In the drawings Figure 1 is a side elevation of a welt and turn sewing machine embodying the features of the invention in their preferred forms, showing the parts in the position which they occupy during the sewing operation; Fig. 2 is a similar view on a larger scale showing the head of the machine with the parts in the position which they occupy after the machine has been brought to rest at the end of the sewing operation; Fig. 3 is a vertical sectional elevation through the axis of the cam shaft, the parts being in the same position indicated in Fig. 2; Fig. 4 is a horizontal view partly in section with the parts in the same position; Fig. 5 is a view looking toward the left in Fig. 4; certain parts being removed or broken away; Fig. 5^a is a detail view of the locking bolt latch to be described; Fig. 6 is a sectional elevation on line 6—6, Fig. 3, with the parts shown in the position which they occupy after the machine has been stopped; Fig. 7 is a similar view showing the position of the parts during the sewing; Fig. 8 is a detail sectional plan view showing the welt measuring devices and the parts cooperating therewith; Fig. 9 is a detail sectional elevation through the shaft for operating the welt holding and severing devices; Fig. 9^a is a detail plan view of the devices for operating the welt holding and severing devices; Fig. 10 is a sectional detail of the welt holding and severing devices; Fig. 11 is a detail showing the connection between the welt measuring device and mechanism for operating the welt holding and severing devices; and Fig. 12 is a sectional elevation showing the welt measuring devices.

In the drawings the invention is illustrated as embodied in a welt and turn sewing machine such as shown and described in the

application of Andrew Eppler, Serial No. 447,542, filed August 8, 1908. This machine is provided with the curved hook needle 1, the looper 2, the thread finger 3, the welt guide 4, the back gage 5, and a feed point 70 and channel guide (not shown), and these devices are operated through suitable connections by cams carried by the cam shaft 6 of the machine. As is usual in this type of machines, the cam shaft makes one revolution for each cycle of operations performed by the stitch forming and work feeding devices. 75

During the sewing operation the machine is driven through a belt pulley 7 secured to the end of the cam shaft, and connected by a driving belt 8 with a pulley 9 mounted in the base of the machine. The pulley 9 is connected through bevel gears 10 with a sleeve 11 mounted on the driving shaft 12 85 and carrying one member 13 of the main driving clutch. The driving shaft carries the other member 14 of the clutch, and also carries the driving pulley 15 through which motion is imparted to the driving shaft. 90 The engagement of the members of the driving clutch is controlled through a treadle 16 connected with the clutch operating wedge 17. When the treadle is depressed, the members of the driving clutch are forced 95 into engagement, and the machine is driven at a speed depending upon the pressure which the operator applies to the treadle. When the treadle is released the clutch members are disengaged, thus disconnecting the cam 100 shaft of the machine from the driving shaft.

The upward movement of the treadle when it is released also throws into operation the mechanism which reverses the cycle of operations of the stitch forming mechanism to cast off the thread from the needle, and which brings the machine to rest with the parts in proper position for the removal of the shoe. This mechanism, in the construction shown, comprises a reversely 110 driven friction clutch consisting of the clutch members 18 and 18'. The clutch member 18 is formed on a spiral gear 19 which is loosely mounted on the cam shaft 6, and is driven in a direction opposite to the direction of rotation of the cam shaft during the sewing operation by a spiral pinion 20 secured to a shaft 21. The shaft 21 is continuously driven from the driving pulley 15 through a belt 22 passing over a pulley 120 formed on the hub of the pulley 15, and over a pulley 23 secured to the shaft 21. The other member 18' of the clutch is formed on a flange 24 projecting from a sleeve 25 which is loosely mounted upon the cam shaft 6. 125 The sleeve 25 is free to slide longitudinally on the shaft, but is connected to rotate with the shaft by means of a block 26 secured to the pulley 7 and arranged between lugs 27 projecting radially from the sleeve 25. The 130

sleeve is held normally in position with the clutch members out of engagement by a spring 28 arranged in a recess in the block 26 and interposed between the bottom of the 5 recess and the head of a bolt which carries a plate 29 engaging the lugs 27. The normal position of the clutch sleeve is determined by an adjustable stop screw 30 which may be adjusted to maintain the clutch sleeve in 10 proper relation to the clutch member.

When the clutch members 18 and 18' are engaged, they act as a friction brake to absorb the energy due to the momentum of the cam shaft, and after the forward movement of the shaft has ceased the clutch acts to turn the cam shaft in a reverse direction at a comparatively slow speed until the clutch is disengaged, when the cam shaft is brought to rest with the needle and other parts of 15 the stitch forming mechanism in the proper position for the removal of the shoe. The mechanism for engaging and disengaging 20 the clutch at the proper times in the rotation of the cam shaft comprises a cam groove 25 25 31 formed in the sleeve 25 and engaged by a roll on one arm of a bell crank lever 32. The other end of the bell crank lever is provided with a hole 33 adapted to receive a locking pin 34 which is normally held out of 30 engagement with the lever, so that during the normal running of the machine the lever is oscillated idly by the cam. The locking pin is mounted in the end of a slide 35 which is held in normal position by a spring 36. The spring surrounds a bolt 37 extending from the rear end of the slide, and is interposed between a shoulder on the slide and the inner end of an adjustable screw threaded sleeve 38. The bolt 37 carries a nut 39 35 40 which engages the outer end of the sleeve and holds the spring under compression. By adjusting the nut the compression of the spring may be varied, and by adjusting the sleeve 38 the slide may be 45 adjusted to bring the locking pin into proper register with the hole in the end of the lever 33. The locking pin is forced in a direction to engage it with the bell crank lever by a spring 40, and the lower end of the pin is 50 connected with the treadle 16 so that the pin is held down out of engagement with the bell crank lever so long as the treadle is depressed and the main driving clutch is acting to drive the cam shaft of the machine.

55 A latch 41 is also connected with the lower end of the locking bolt, and is arranged to engage a shoulder 42 on the slide 35, and hold the locking bolt in its lower position until the treadle has been raised sufficiently 60 to allow the locking bolt to engage the bell crank lever. In the construction shown, the latch 41 is loosely pivoted on a rock shaft 43, and is connected with the shaft by a pin 44 projecting through a slot in the hub of 65 the latch (Figs. 4, 5 and 5a). The rock shaft

43 is mounted in a block 45 secured on the lower end of the locking bolt, and carries an arm 46 which is connected by a link 47 with the treadle 16. When the treadle is depressed the rock shaft 43 turns until the latch 41 brings up against the slide 35, and then during the continued downward movement of the treadle the locking bolt is drawn down against the tension of its spring. This carries the latch 41 under the shoulder 42. When the treadle is released the latch 41 prevents the upward movement of the locking pin, and the rock shaft 43 is rocked until the pin 44 strikes the end of the slot in the hub of the latch and swings the latch outward, thus disengaging it from the shoulder 42. When this takes place the spring forces the pin upward against the under side of the bell crank lever, and when the hole in the lever registers with the pin the pin snaps up 85 into the hole, thus connecting the lever with the slide 35.

The cam 31 is so timed that the hole in the end of the bell crank lever is brought into position to register with the locking pin at the proper time in the cycle of operations of the stitch forming mechanism. When the pin is engaged with the bell crank lever the lever is held from movement about its pivot, and the cam 31 acting on the roll carried by the lever, shifts the clutch sleeve 25 to bring the members of the reversing clutch into engagement. When the lever and slide 35 are locked together by the locking pin, the movement of the lever is resisted by the spring 36, and the force with which the members of the friction clutch are pressed together will depend upon the compression of the spring. This may be adjusted to secure the desired braking effect between the members of the friction clutch so that the forward rotation of the cam shaft will be arrested within the desired part of a revolution. In the construction shown, the parts are so timed and controlled that the locking bolt is engaged with the lever and the friction clutch engaged while the needle is retracted, and just before it begins its advance movement, and the forward rotation of the cam shaft is arrested after the needle has advanced and entered the work. The clutch then acts to turn the cam shaft in a reverse direction at a slow speed until the shaft arrives at the point where the cam 31 acted to engage the members of the clutch, when the reversely moving cam acts to again disengage the clutch members. The cam shaft is therefore brought to rest with the needle in its retracted position, and the other parts of the stitch forming mechanism in such position that they do not interfere with the removal of the shoe. The reversal of the cycle of operations after the needle has penetrated the stock causes the needle to be retracted without a loop of thread in its hook, and 120 125 130 135 140 145 150 155 160 165 170 175 180

consequently the last loop drawn by the needle is cast off so that the needle is automatically freed from the thread.

When the reversing clutch is disengaged, the reverse movement of the cam shaft may be finally stopped by a friction brake applied to one of the cam disks on the shaft, or by a positive stop, or both means may be employed, in which case the positive stop 10 acts as a safety device to prevent any accidental overrunning of the cam shaft. In the construction shown, both devices are employed. As shown, the stop comprises a stop arm 48 secured to a rock shaft 49 and having its end arranged to be moved into and out of the path of a stop shoulder 50 on a disk 51 which is secured to the cam shaft. The rock shaft 49 is the shaft which is actuated by the reversal of the cam shaft to 20 throw off the thread tension in the machine of the Eppler application above referred to. This shaft carries an upwardly projecting arm 52, to the upper end of which is pivotally connected the actuating lever 53. The front end of the lever is provided with two 25 segmental surfaces, the upper one of which runs against a sleeve on the cam shaft during the forward rotation of the cam shaft, as indicated in Fig. 7. With the lever in 30 this position, the stop 48 is out of the path of the shoulder 50. When the rotation of the cam shaft is reversed, a notch in the sleeve acts on the lever 53 and rocks it into the position indicated in Fig. 6, thus rocking the shaft 49 to throw off the thread tension, 35 and also to bring the stop arm 48 into the path of the shoulder 50. The friction brake for stopping or assisting in stopping the reverse rotation of the cam shaft is indicated 40 at 48' and is connected to the arm 52 so that the rock shaft 49 applies the brake as well as operating to bring the stop arm 48 into the path of the shoulder 50. With this construction the frictional engagement of the 45 members of the reversing clutch acts to gradually arrest the forward rotation of the cam shaft without undue shock or jar, and still allows sufficient forward movement of the needle to free the loop of thread carried thereby from the hook of the needle. After 50 the needle has been thus advanced and the forward rotation of the cam shaft arrested, the reversing clutch operates to turn the cam shaft in a reverse direction at a 55 comparatively slow and at a uniform speed, which is unaffected by the speed of the machine at the time the main driving clutch is disengaged. The machine is therefore finally brought to rest when moving at a uniformly 60 slow speed, thus avoiding undue shock or jar, and insuring a reliable and uniform operation of the reversing and stopping mechanism.

After the sewing operation has been completed, and the machine has been brought to

rest with the needle free from the thread, and the stitch forming devices in position for the removal of the shoe, the welt is severed and the severed end of the welt held in position for attachment to a shoe at the beginning of the next sewing operation. The devices for severing and holding the welt, in the construction shown, comprise the welt gripping jaws 54 and 55 and the welt severing knife 56 which are held in retracted position during the sewing of the shoe, and are advanced to sever and hold the welt after the sewing operation has been completed and the machine brought to rest. The welt holding jaws are carried upon the front end of a bar 57 mounted to slide in a carrier arm 58 which is in turn mounted to swing about a vertical shaft 59. The shaft 59 is mounted in a bearing in a fixed bracket 60, and the carrier arm 58 is held in normal position against a stop 61 by a spring 62. The upper jaw 54 is fixed on the end of the bar 57, while the lower jaw 55 is pivotally supported on the bar by an eccentric pivot 63 which may be turned to adjust the jaw 55 70 with relation to the jaw 54. The bar 57 is recessed to form a guide for the knife carrying bar 64, to the forward end of which the knife 56 is secured. The knife carrying bar is provided at its forward end with a cam surface 65 arranged to engage the rear end of the pivoted jaw 55 and close the welt holding jaws. The rear end of the jaw 55 is slotted to form a spring arm so that the jaw 75 may yield to accommodate itself to variations in the thickness of the welt. The gripper carrying bar 57 is advanced and retracted through a gear segment 66 secured to the shaft 59 and engaging a rack formed on the bar. The cutter carrying bar 80 is independently reciprocated by a pinion 67 secured to the shaft 59 and engaging a rack formed on the bar. The shaft 59 is oscillated to advance and retract the welt holding jaws and cutter through a gear segment 68 engaging a pinion formed on the upper end 85 of the shaft. The gear segment is secured to a rock shaft 69 which is automatically actuated at proper times through an arm 70 secured to the end of the shaft and connected with a strap 71 which surrounds and is operated by an intermittently operating eccentric 72. The eccentric 72 is formed on a sleeve 73 mounted to turn freely about the hub of the continuously rotating spiral gear 110 19. The eccentric is intermittently rotated through a half revolution by means of a roll clutch adapted to intermittently connect the eccentric carrying sleeve with the spiral gear. As shown, this clutch comprises one 115 or more rolls 74 interposed between flat surfaces 75 on the eccentric carrying sleeve, and a surrounding wear ring 76 carried by the spiral gear. The rolls are controlled by a 120 roll carrying ring 77 provided with project- 125 130

ing lugs 78 between which the rolls are located. A spring 79 connects the eccentric carrying sleeve and roll carrying ring, and tends to move the ring in a direction to wedge the rolls between the flat surfaces on the sleeve and the wear ring to engage the clutch. Spring latching pins 79' hold the sleeve 73 against backward movement. The roll carrying ring is held in position to hold the rolls out of action by one or the other of two latches 80 and 81 which are adapted to engage a stop dog 82 carried by the ring. During the operation of the machine in sewing, the dog 82 is in engagement with the latch 80, as indicated in Fig. 7. When the parts are in this position the eccentric 72 and the connected gear segment 68 are in position to hold the gripper carrying bar and knife carrying bar in the retracted position indicated in Fig. 7. When the parts are in this position the lower jaw is held in open position by the engagement of the rear end of the jaw with a cam lug 83, and the jaws are in position where they do not interfere with the manipulation of the shoe during the sewing operation.

After the sewing operation has been completed and the welt is to be severed, the latch 80 is raised to release the roll carrying ring 30 of the actuating clutch. This throws the clutch into action, and the eccentric carrying sleeve is rotated through a half revolution and until the dog 82 engages the latch 81, thus disengaging the clutch. This half revolution of the eccentric rocks the gear segment 68 from the position indicated in Fig. 7 to the position indicated in Fig. 6, and turns the shaft 59 in a direction to advance the welt gripper and cutter bars. The 40 bars move forward in unison until the jaws of the welt holder have passed on opposite sides of the welt, and the guard 84 on the lower jaw has engaged the inner edge of the welt. When the gripper bar reaches this 45 position the teeth of the gear segment 66 pass from engagement with the teeth of the rack on the bar, and the bar is held locked in position by the engagement of a locking segment 85 formed on the gear with a locking segment 86 formed on the bar. During the continued movement of the shaft 59 the gear 67 continues to advance the cutter bar. During the first part of the advance movement of the cutter bar with relation to the 55 gripper bar the cam 65 on the cutter bar closes the welt holding jaws, and during the continued forward movement of the cutter bar the knife 56 acts to sever the welt. The parts are now in the position indicated 60 in Figs. 3 and 4, with the welt holding jaws firmly gripping the severed end of the welt supply beyond the welt guide, and holding it in proper position for attachment to a shoe at the beginning of the next 65 sewing operation. The parts remain in this

position until the machine is started at the beginning of the sewing operation on the succeeding shoe. At the beginning of the sewing operation on the next shoe, the welt holding jaws continue to hold the end of the welt until after the welt guide has been withdrawn from the shoe, and until the initial feed of the shoe has been completed, and during the feed of the shoe the arm carrying the cutter and gripper bars is 70 swinging about the shaft 59 so that the welt holding jaws move forward with the shoe and hold the end of the welt in proper relation to the shoe, and also draw the welt through the welt guide so that all danger 75 of displacement of the welt is avoided. In the construction shown, the carrier for the welt holding jaws is actuated to move the jaws with the shoe during the initial feed 80 through connection with the feed slide 85 which carries the awl and channel guide. As shown, this connection comprises a bar 87 one end of which is adjustably secured to the feed slide through a split bearing and clamping bolt 88 (Fig. 7), and the other end 89 of which is provided with a depending finger 89 arranged to coöperate with a yielding dog 90 carried by the gripper bar 57. The dog 90 is pivoted on the gripper bar and is held normally in raised position by a spring. 95 This yielding dog is provided in order that the welt holder may not be moved in the direction of the feed by the slight forward movement of the feed slide which occurs upon starting the machine prior to the initial forward stroke of the needle.

When the machine is brought to rest the feed slide is usually in such position that it will move forward slightly when the machine is started. With the feed slide in this 105 position the finger 89 is in the path of the dog 90 when the gripper carrying bars advance to bring the jaws of the welt holder into position to grip the welt, and the dog yields and rides under the end of the finger, 110 as indicated in Fig. 2. When the machine is started the finger still rides on the top of the dog 90 when the feed slide is given its slight forward movement, but on the return movement of the feed slide preparatory to 115 the initial feed of the shoe the finger 89 passes to the right of the dog 90, so that the dog snaps up into position in front of the finger. Now during the advance movement of the feed slide in giving the initial feed to the shoe, the finger 89 bears against the right-hand side of the dog 90 and swings the arm 58 about the shaft 59, so that the welt holding jaws move with the shoe during its initial feed. As the initial feed of the 120 shoe is completed the latch 81 which holds the actuating clutch for the welt holder and cutter out of operation is operated to release the roll carrying ring and thus throw the clutch into operation. The latch 81 is thus 125 130

operated by a cam groove 91 formed in the face of the cam disk 51 and engaging a roll on the end of an arm 92 which is secured to the rock shaft 93 carrying the latch. When 5 the latch 81 is thus operated to engage the actuating clutch, the clutch and eccentric 72 are rotated through a half revolution and until the dog 82 engages the latch 80 and throws the clutch out of operation. This 10 semi-rotation of the eccentric rocks the gear segment 68 from the position indicated in Fig. 6 to the position indicated in Fig. 7, thus operating the shaft 59 to retract the gripper bar and knife bar. During the rotation 15 of the shaft 59 the gear 67 first retracts the cutter bar independently of the gripper bar, and then the cutter and gripper bars are moved in unison to their rearward position. The movement of the cutter bar 20 with relation to the gripper bar, causes the cam 65 to release the gripper jaw 55 so that it may swing away from the welt, and during the return movement of the gripper bar the rear end of the jaw rides up the lug 83, so 25 that the jaw is positively opened. The return movement of the gripper bar also withdraws the dog 90 from engagement with the finger 89, so that the carrier arm 58 is returned to normal position against the stop 30 61 by the spring 62. This brings the parts into their normal position where they remain during the completion of the sewing operation and until the gripper and cutter bars are to be again advanced to sever and 35 hold the welt. In order that the dog 82 may not interfere with the return movement of the latch 81, in case the latch is swung forward before the dog has completely passed from under it, the dog is yieldingly mounted 40 in the roll carrying ring as indicated in Figs. 6 and 7.

The latch 80 which throws the actuating clutch into operation to advance the welt holder and cutter to sever and hold the welt 45 may be actuated by any suitable devices under the control of the operator. To relieve the operator of additional manipulations, and to increase the rapidity with which the shoe may be freed and removed, it is preferred, however, to control the latch by the forward movement of the shoe in bringing the welt into proper position for the operation thereon of the cutting and holding devices. In order that the welt may be severed at a suitable distance from the end of a completed seam without waste of welting, devices are provided for determining the extent to which the welt may be advanced or pulled through the welt guide in withdrawing 55 the shoe preparatory to the operation of the welt severing and holding devices. For the sake of simplicity, these devices are connected with the clutch controlling latch 80 so that their movement when the welt is drawn 60 forward raises the latch and thus throws the

actuating mechanism for the welt cutter and holder into operation. In the construction shown the devices for determining or limiting the forward movement of the welt are rendered active or thrown into operation by 70 the reverse movement imparted to the cam shaft of the machine in freeing the needle from the loop and bringing the parts into position for the removal of the shoe, and are rendered inactive by the forward movement 75 of the cam shaft at the beginning of the next sewing operation. The devices are thus rendered active at the proper time without any attention on the part of the operator, and are inactive during the normal operation of 80 the machine.

As shown, the welt W is led to the welt guide over a guide pulley 94 which is mounted to turn freely on a controlling or measuring shaft 95 which carries a clamping jaw 96 adapted to engage and clamp the welt against the pulley 94. The clamping jaw is carried in one arm of a bell crank lever 97, the other arm of which is arranged to be engaged by the end of a plunger 98 90 mounted within the shaft 95. The clamp is held normally out of engagement with the welt by a spring 99. The movement of the measuring shaft is limited by a stop pin 100 arranged to enter a slot 101 formed in 95 an arm 102 secured to the rear end of the shaft. An adjusting stop screw 103 is mounted in the arm in position to engage the stop pin, and by adjusting this screw the extent to which the measuring shaft may 100 be turned may be varied. The clamp actuating plunger 98 is formed in two sections separated by a spring 104 which may yield as the plunger is advanced in forcing the clamp against the welt to accommodate 105 variations in the thickness of the welt. The rear end of the plunger is engaged by a cam shoe 105 adjustably secured to one arm 106 of a bell crank lever, the other arm 107 of which is arranged to engage and be operated by the arm 52 when this arm is rocked by the reverse movement of the cam shaft at the completion of the sewing operation. When the bell crank lever 107—106 is thus rocked at the completion of the 110 sewing operation, the cam shoe 105 forces the plunger 98 forward so that the clamp 96 is engaged with the welt. Now when the shoe is drawn forward to draw the welt through the welt guide, the measuring shaft 115 is rotated until the end of the slot 101 brings up against the stop pin 100, when further advance movement of the welt is prevented. The length of the slot 101 therefore determines the extent to which the welt 120 may be drawn forward in removing the shoe and bringing the welt into proper position for the operation of the welt serving and holding devices. The rotation of the shaft 95 by the forward movement of the 125

65 130

welt also raises the latch 80 and throws the actuating devices for the welt severing and holding mechanism into operation. The connections through which the latch is raised consists of a link 108 connecting the end of the arm 102 with an arm 109 secured to the rock shaft 110 which carries the latch 80.

When the machine is started at the beginning of the sewing operation upon the next shoe, the arm 52 moves toward the right in Fig. 6, rocking the shaft 49 in the manner already described. When this movement of the arm and rock shaft takes place, the rock shaft 110 is actuated to bring the latch 80 down into the path of the dog 82, and to also rock the measuring shaft 95 to return the measuring shaft to its normal position indicated in Fig. 11. This movement of the arm 52 also releases the bell crank lever 107—106 so that the spring 99 may disengage the clamp 96 from the welt. The connection through which the rock shaft 110 is actuated from the rock shaft 49 consists of a link 111 connecting the latch arm 48 with an arm 112 secured to the shaft 110. The upper end of the link 111 slides freely through a hole in the arm 112 and is provided with nuts 113. When the shaft 49 is rocked by the reverse rotation of the cam shaft at the completion of the sewing operation, the link 111 slides idly up through the arm 112 so that the shaft 110 is free to be rocked by the forward movement of the welt in the manner above described. When the shaft 49 is rocked in the opposite direction at the beginning of the next sewing operation, the nuts 113 engage the arm 112 and rock the shaft 110 in a direction to bring the latch 80 into the path of the dog 82, and to return the welt measuring device to normal position, in which position it will be locked against forward rotation so long as the cam shaft rotates forwardly (and until the shaft 49 is again rocked, as above described, at the completion of the sewing operation) by reason of the continued engagement of nut 113 with the arm 112. It follows, therefore, that any tendency of the shaft 95 and its connected parts to rotate and thereby to raise the latch 80 out of engagement with dog 82, thus causing the welt severing and holding mechanism to be thrown into operation, is resisted by the nuts 113 throughout the entire sewing operation. Thus, if, during the sewing of a shoe and the progressive forward travel of the welt W, a portion of the welt which at the time is passing between guide pulley 94 and clamping jaw 96 is twisted or is thicker than normal, or if any other condition exists as a result of which the forward pull on the welt tends to effect the rotation in a forward direction of the pulley, jaw and shaft 95, such rotation is

prevented by nuts 113 and parts connected therewith. These devices thus maintain the welt severing and holding mechanism in retracted position while the shoe is being sewn after the welt has been properly secured thereby, and constitute one form of means for preventing the operation of the welt severing or welt severing and holding devices during the sewing operation. 70

By the devices and mechanisms referred to the time consumed in removing a finished shoe and presenting another shoe to the machine is reduced to a minimum, and the capacity of the machine thus increased. No manipulation of the machine by the operator, aside from releasing the treadle, is required in order to free the needle from the thread and bring the parts into proper position for the removal of the shoe, or to throw the welt severing and holding devices 85 into operation. After the machine has been reversed and stopped by the reverse driving and stopping mechanism, the operator merely draws the shoe forward to withdraw the welt slightly from the welt guide, and in so doing throws into operation the welt severing and holding devices, which immediately sever the welt from the shoe and hold the end of the welt supply in position to be attached to the succeeding shoe. This 90 frees the shoe from the welt, so that the operator may carry the shoe upward to engage the thread leading from the shoe to the thread supply with a thread severing and holding device indicated at 114 in Fig. 100 1, thus completely freeing the shoe from the machine. In beginning the sewing operation upon the succeeding shoe the operator merely places the shoe in proper position with relation to the stitch forming devices 105 and depresses the treadle, the starting of the machine causing the welt measuring devices and the welt severing and holding devices to be returned to normal position after the end of the welt has been properly connected to the shoe by the stitch forming 110 mechanism.

While the main features of the invention are particularly applicable to a sewing machine for connecting the welt and upper to the insole of a welt shoe, and the invention has been shown and described as embodied in such a machine, it will be understood that certain features of the invention are not limited in their application to such a 120 machine, but may be embodied with advantage in various shoe sewing or other machines. It will also be understood that the specific construction and arrangement of the parts shown and described is not essential 125 to the broader features of the invention, and may be varied or modified without departing therefrom.

Having explained the nature of and object of the invention, and specifically de- 130

scribed one form of machine in which it may be embodied, what I claim is:—

1. A sewing machine, having, in combination, stitch forming devices and mechanism for reversing the cycle of operations upon stopping the machine comprising braking means for retarding the forward movement of the machine, and slow speed reverse driving means for returning the machine to 10 stopping position, substantially as described.

2. A sewing machine, having, in combination, stitch forming devices and mechanism for reversing the cycle of operations upon stopping the machine comprising means for absorbing the energy due to the forward movement of the machine and returning the machine to stopping position at a predetermined slow speed, substantially as described.

3. A sewing machine, having, in combination, stitch forming devices and mechanism for reversing the cycle of operations upon stopping the machine comprising means for reducing the speed of the machine and means for thereafter driving the machine in a reverse direction to stopping position at a uniform slow speed, substantially as described.

4. A sewing machine, having, in combination, stitch forming devices and mechanism for reversing the cycle of operations upon stopping the machine comprising reverse driving mechanism constructed to first act as a friction brake to gradually arrest the forward movement of the machine and to then drive the machine at a slow speed back 35 to its stopping point, substantially as described.

5. A sewing machine, having, in combination, stitch forming devices and mechanism for reversing the cycle of operations upon stopping the machine comprising a reversing friction clutch and means for engaging the clutch at a predetermined point in the cycle of operations of the machine and for disengaging it at a predetermined point in 45 the reverse movement of the machine, substantially as described.

6. A sewing machine, having, in combination, stitch forming devices and mechanism for reversing the cycle of operations upon 50 stopping the machine comprising reverse driving mechanism having provision for frictionally resisting the forward movement of the machine when thrown into operation, and means for throwing the reverse driving 55 mechanism out of operation and stopping the machine at a predetermined point in its reverse movement, substantially as described.

7. A sewing machine, having, in combination, stitch forming devices and mechanism for reversing the cycle of operations upon 60 stopping the machine comprising reverse driving mechanism having provision for frictionally resisting the forward movement 65 of the machine when thrown into operation,

and means for throwing said reverse driving mechanism into operation at a predetermined point in the cycle of operations of the machine, substantially as described.

8. A sewing machine, having, in combination, stitch forming devices, driving mechanism therefor, a braking and reversing driving mechanism, means for throwing said braking and reverse driving mechanism into and out of operation including a timing cam, 70 and means for rendering said cam active when the main driving mechanism is thrown out of operation, substantially as described.

9. A sewing machine, having, in combination, stitch forming devices, driving mechanism therefor, a braking and reverse driving mechanism, means for throwing said braking and reverse driving mechanism into and out of operation including a timing cam 80 and a normally inactive actuating lever, and means for rendering said lever and cam active when the main driving mechanism is thrown out of operation, substantially as described.

10. A sewing machine, having, in combination, stitch forming devices, driving mechanism therefor, a braking and reverse driving mechanism, means for throwing said braking and reverse driving mechanism into action when the main driving mechanism is thrown out, and means for throwing it out of action and stopping the machine at a predetermined point, substantially as described.

11. A sewing machine, having, in combination, stitch forming devices, a cam shaft from which they are actuated, a driving clutch, a reversely driven slow speed friction clutch, devices driven from the cam shaft for engaging and disengaging the low speed clutch, and means for rendering said latter devices active when the driving clutch is thrown out in stopping the machine, substantially as described.

12. A sewing machine, having, in combination, stitch forming devices, a cam shaft from which they are actuated, driving mechanism including a starting and stopping treadle, a reversing clutch comprising a friction clutch member connected to rotate with the cam shaft, a cam driven by the clutch member, an actuating lever operated by the cam, and a locking pin operated by the treadle for rendering the lever and cam active to shift the clutch member when the treadle is actuated to stop the machine, substantially as described.

13. A sewing machine, having, in combination, stitch forming mechanism, welt severing and holding devices, and power driven mechanism controlled by the operator for actuating said devices to sever and hold the welt, substantially as described.

14. A sewing machine, having, in combination, stitch forming mechanism and

mechanism for severing the welt and means for throwing the severing mechanism into operation by a movement of the shoe after the completion of the sewing, substantially as described.

15. A sewing machine, having, in combination, stitch forming mechanism and mechanism for severing the welt and means for throwing the severing mechanism into operation by a forward pull on the welt after the completion of the sewing, substantially as described.

16. A sewing machine, having, in combination, stitch forming mechanism and mechanism for severing and holding the welt and means for throwing the severing and holding mechanism into operation by a movement of the shoe after the completion of the sewing, substantially as described.

17. A sewing machine, having, in combination, stitch forming mechanism and mechanism for severing and holding the welt and means for throwing the severing and holding mechanism into operation by a forward pull on the welt after the completion of the sewing, substantially as described.

18. A sewing machine, having, in combination, stitch forming mechanism, means for limiting the withdrawal of the welt upon the removal of the shoe, and devices thrown into operation by the welt limiting means for severing the welt, substantially as described.

19. A sewing machine, having, in combination, stitch forming mechanism, means for limiting the withdrawal of the welt upon the removal of the shoe, and devices thrown into operation by the welt limiting means for severing and holding the welt, substantially as described.

20. A sewing machine, having, in combination, stitch forming mechanism, mechanism for reversing the cycle of operations upon stopping the machine, means rendered active by the reversal of the machine for limiting the withdrawal of the welt upon the removal of the work, and means controlled by the withdrawal of the welt for severing and holding the welt, substantially as described.

21. A sewing machine, having, in combination, stitch forming mechanism, a welt measuring device mounted for limited movement with the welt, adjusting means for determining the movement of the device with the welt, and means for connecting the device with the welt at the completion of the sewing and for disconnecting it from the welt and returning it to initial position at the beginning of the sewing, substantially as described.

22. A sewing machine, having, in combination, stitch forming mechanism, welt severing and holding devices, an intermit-

tently operating clutch for alternately actuating and withdrawing said devices, a welt measuring device connected to throw the clutch into operation to actuate the welt holding and severing devices, and a cam for throwing the clutch into operation to withdraw the welt holding and severing devices, substantially as described.

23. A sewing machine, having, in combination, stitch forming mechanism, welt severing and holding devices, an intermittently operating clutch for alternately actuating and withdrawing said devices, a welt measuring device having a limited movement with the welt upon the removal of the work, a clutch controlling latch connected to the measuring device, and a clutch controlling latch operated upon the starting of the machine, substantially as described.

24. A sewing machine, having, in combination, stitch forming mechanism, mechanism for reversing the cycle of operations upon stopping the machine, welt severing and holding devices, a welt measuring device having a limited movement with the welt upon the removal of the work and engaged with the welt by the reversal of the machine, an intermittently operating clutch for actuating and withdrawing the welt severing and holding devices, a clutch controlling latch connected with the welt measuring device, and a clutch controlling latch operated upon the starting of the machine, substantially as described.

25. A sewing machine, having, in combination, stitch forming mechanism, actuating mechanism therefor including a cam shaft, a stop pawl arranged to arrest the backward rotation of the cam shaft at a predetermined point, and means for holding the pawl in inactive position during the forward running of the machine and means for moving it into active position by the reversal of the cam shaft.

26. A sewing machine, having, in combination, stitch forming mechanism, welt severing devices, actuating mechanism therefor, and mechanism rendered operable upon the completion of the sewing for throwing the actuating mechanism of the welt severing devices into operation.

27. A sewing machine, having, in combination, stitch forming mechanism, welt severing and holding devices, actuating mechanism for the welt severing and holding devices, and mechanism rendered operable upon the completion of the sewing for throwing the actuating mechanism into operation.

28. A sewing machine, having, in combination, stitch forming mechanism, devices for severing the welt, actuating mechanism for the welt severing devices, and mechanism rendered operable at the completion of the sewing for throwing the actuating

mechanism into operation by a pull on the welt.

29. A sewing machine, having, in combination, stitch forming mechanism, welt severing devices, actuating mechanism for the welt severing devices, devices for throwing the actuating mechanism into operation, and means for preventing the operation of said devices during the sewing and for rendering them operable upon the completion of the sewing.

30. A sewing machine, having, in combination, stitch forming mechanism, devices for severing the welt, and means for preventing the operation of the welt severing devices during the sewing.

31. A sewing machine, having, in combination, stitch forming mechanism, devices for severing and holding the welt, and means for preventing the operation of the welt severing and holding devices during the sewing.

32. A sewing machine, having, in combination, stitch forming mechanism, devices

for severing the welt, actuating mechanism 25 for the welt severing devices, mechanism rendered operative upon the completion of the sewing for throwing the actuating mechanism into operation by a pull on the welt, and means for preventing the throwing in 30 of the actuating mechanism during the sewing.

33. A sewing machine, having, in combination, stitch forming mechanism, devices for severing the welt, actuating mechanism 35 for the welt severing devices, and means rendered inactive by the reversal of the machine for preventing the operation of the welt severing devices during the sewing.

34. A sewing machine, having, in combination, stitch forming mechanism, a welt severing device, and actuating means for said device the operation of which is dependent upon the reversal of the machine.

LAURENCE E. TOPHAM.

LESTER A. HOWE.

Copies of this patent may be obtained for five cents each, by addressing the "Commissioner of Patents, Washington, D. C."

It is hereby certified that in Letters Patent No. 1,099,326, granted June 9, 1914, upon the application of Laurence E. Topham, of Beverly, Massachusetts, for an improvement in "Sewing-Machines," errors appear in the printed specification requiring correction as follows: Page 4, line 59, for the word "when" read *while*; page 6, line 128, for the word "serving" read *severing*; and that the said Letters Patent should be read with these corrections therein that the same may conform to the record of the case in the Patent Office.

Signed and sealed this 4th day of August, A. D., 1914.

[SEAL.]

J. T. NEWTON,
Acting Commissioner of Patents.
